Godfrey L. Dé Caccia, 8162 Bellhaven Ave.,
La Palma, Calif. 90620

Filed Nov. 22, 1966, Ser. No. 5,363

Term of patent 14 years

(Cl. D55—1)

FIG. 1.

FIG. 2.

FIG. 3.

FIG. 4.

FIG. 5.

FIG. 6.

FIG. 1 is a perspective view of a combined tool holder and parts tray showing my new design, embodied in a combined tool holder and parts tray with a work surface;

FIG. 2 is an elevation as seen from the right of FIG. 1;

FIG. 3 is a rear elevation thereof;

FIG. 4 is an enlarged fragmentary top plan view of the right rear portion of said tray;

FIG. 5 is a perspective view of a modified form of a combined tool holder and parts tray shown in FIG. 1, wherein the work surface is omitted therefrom;

FIG. 6 is an end elevation as seen from the right of FIG. 5.

This application is a continuation-in-part of design application Ser. No. D.609, filed Jan. 14, 1966 and now abandoned.

I claim:

The ornamental design for a combined tool holder and parts tray, as shown and described.
